ATTORNEY.

UNITED STATES PATENT OFFICE.

ALFRED F. BERNARD, OF OSKALOOSA, IOWA.

DESIGN FOR A NUT-LOCK.

SPECIFICATION forming part of Design No. 25,915, dated August 11, 1896.

Application filed April 15, 1896. Serial No. 587,734. Term of patent 14 years.

To all whom it may concern:

Be it known that I, ALFRED F. BERNARD, a citizen of the United States, residing at Oskaloosa, in the county of Mahaska and State of Iowa, have invented and produced a new and original Design for Nut-Locks, of which the following is a specification.

The figure in the drawing is a side view showing the shape and configuration of my nut-lock for ordinary rail-joints.

The leading feature of my design consists of the three hexagon-shaped loops a' a^2 a^3 , a nearly-horizontal stretch c , connecting between the bottom of one end loop and the bottom of the middle loop, and an inclined

stretch c' , connecting from the bottom of the middle loop to near the top of the other loop.

The contour and appearance of the three loops are the same, but the two connecting-stretches c c' differ, one being horizontal 20 while the other is inclined.

Having thus described my design, I claim—
The design for a nut-lock as herein shown and described.

In testimony whereof I affix my signature 25 in the presence of two witnesses.

ALFRED F. BERNARD.
